2 Sheets-Sheet 2

UNITED STATES PATENT OFFICE

SWAN SMITH, OF WHITE BEAR, MINNESOTA, ASSIGNOR TO ORENDA CORPORATION, OF CHICAGO, ILLINOIS, A CORPORATION OF ILLINOIS

PAPER FORMING MACHINE

Application filed September 29, 1930. Serial No. 425,005.

My invention relates to methods of and apparatus for longitudinally grooving strips or sheets of paper and has for an object to provide an improvement in the method of 25 and apparatus for forming sheets with longitudinal grooves disclosed in my co-pending application, Serial No. 343,495, filed February 28, 1929.

In employing the method and apparatus 10 of my said co-pending application in the forming of a substantial number of parallel grooves longitudinally of a strip or sheet of very inferior paper, it has been noted that such stock tends to fracture, between the innermost grooves, on account of the relatively heavy stress placed upon the comparatively weak paper, at the central zone thereof, during the initial gathering of the sheet along such zone.

An object of my present invention is to 20 make such provision as will reduce such stresses in the gathering of the paper and thereby permit of the utilization of relatively inexpensive paper without the danger of 25 such paper being torn or otherwise injured in the gathering and forming thereof.

As in the invention disclosed in my said co-pending application, material is gathered along a central zone of a moving sheet of 30 paper by means of gathering rolls designed partially to form the innermost of the grooves ultimately to be formed in the strip, said grooves being later completely formed by forming rolls concurrently with the gathering of stock and the partial formation of 35 grooves therein along zones at either side of said central zone. And, as in said prior invention, the progressive gathering and formation of the paper stock continues, the strip, grooved longitudinally from center to 40 either side thereof, emerging fully formed as a completed product or for further operations as the case may be.

In the present invention, I employ a pair 45 of initial rolls designed solely for the purpose of gathering stock at the center of the moving sheet, one roll having a relatively large gradually curved bulge thereon, and the other roll having a groove corresponding 50 with and cooperating with said bulge. These

initial rolls operate to draw inwardly toward the center of the sheet an appreciable amount of the stock without giving to the same any particularly definite form, which portion of the stock is available, without strain, for the 55 formation of the offsets and the ultimate grooves by the subsequent gathering and forming rolls.

Another object of the invention resides in providing a device for adjusting the spacing 60 of the initial gathering rolls to vary the quantity of material gathered thereby.

Other objects of the invention reside in the novel combination and arrangement of parts and in the details of construction hereinafter illustrated and/or described.

In the drawings:

Figure 1 is a plan view of a machine illustrating a structural embodiment of my invention.

Figure 2 is an elevational view of the structure shown in Figure 1 with some of the gearing removed to illustrate the method of journaling the rolls.

Figure 3 is an elevational sectional view 75 taken on line 3-3 of Figure 1.

Figure 4 is a cross sectional view taken on the line 4-4 of Figure 1.

Figure 5 is a fragmentary elevational sectional view taken on the line 5-5 of Figure 80 2 and drawn to a larger scale.

Figure 6 is a plan sectional view of the structure shown in Figure 5 taken on line 6-6 of Figure 2.

My improved method and machine are 85 capable of numerous uses and applications and are especially useful in the manufacture of grooved egg flats constructed as shown in my said application, Serial No. 343,495, and which involve in their development the formation of longitudinal grooves in a moving strip or sheet of paper stock.

The machine illustrated in the drawings 95 includes two longitudinal frame members 10 and 11 connected by means of a number of transverse bars 12, 13 and 14 secured to said longitudinal frame members by means of bolts 16. The frame members 10 and 11 are provided with legs 15 for supporting the machine. Between the two frame members 10 100

and 11, as will be seen in Figure 3, are rotatably mounted eight lower rolls 17, 18, 19, 20, 21, 22, 23 and 24, and immediately above them are mounted eight complementary rolls 25, 26, 27, 28, 29, 30, 31 and 32. Each of the lower rolls 17 to 24 inclusive is formed with trunnions 33 (Figures 2, 5 and 6) which are journaled in bearings 35 mounted on the frame members 10 and 11. The upper rolls 25 to 32 inclusive are similarly constructed with trunnions 36 journaled in bearings 38 which are movable within openings 47 formed in the frame members 10 and 11 directly above the bearings 35. Thus movable, the bearings 38 may be moved toward and from the bearings 35 to vary the distance between the rolls of the different pairs thereof. The bearings 38 are constructed with vertical slots 50 which receive guides 51 embodied in the frame members 10 and 11. The rolls of the different pairs are normally held apart by means of coil springs 42 (Figure 5) which are seated in sockets 43 in the bearings 38 and in corresponding sockets 44 in the bearings 35. By applying pressure to the bearings 38 they may be forced downwardly along the guides 51 toward the bearings 35 in opposition to the springs 42 to vary the distance between the upper and lower rolls of the different pairs thereof.

For the purpose of maintaining the rolls in adjusted position, each of the frame members 10 and 11 is provided with a longitudinal bar 45 resting upon the upper edge thereof. These bars are secured to the frame members 10 and 11 by means of bolts 46 screwed into the portions 37 thereof between the openings 47. Centrally disposed with respect to said openings 47 are adjusting screws 48 threaded into the bars 45 in positions immediately above the bearings 38. By turning these screws 48 in one direction, the bearings 38 may be depressed toward the bearings 35 in opposition to the springs 42 and, by turning said screws in the opposite direction, a reverse movement of said bearings may be had through the action of said springs. Thus the various rolls may be quickly and accurately adjusted relative to one another at will. Holding the adjusting screws 48 in locked position are lock nuts 49 which are threaded upon said screws and seated against the bars 45.

The various rolls 17 to 24 inclusive are all driven in a counterclockwise direction as viewed in Figure 2 and at the same rate of speed. The rolls 25 to 32 inclusive are driven in a clockwise direction and at the same rate of speed with respect to each other and to the rolls 17 to 24 inclusive. By means of such rotation, a strip or sheet inserted between the various rolls is continuously fed and moved along between them and is formed in a manner now to be explained.

65 The roll 32 (Figures 1 and 3) is formed

medially thereof with two annular offsets or shoulders 52 and 53, its companion roll 24 being constructed with similar shoulders 55 (Figure 3). These shoulders are disposed in an offset relation with respect to one another so that as a sheet passes between the rolls 32 and 24, a gathering of stock occurs at the center thereof in the formation in the sheet of offset portions which are subsequently finally formed into grooves.

The roll 31 (Figures 1 and 3), succeeding roll 32, is provided with two annular beads 64 and 65 of cross sectional shape and form corresponding with the finished grooves of the sheet. These beads are arranged substantially in alignment with the shoulders 52 and 53 of the preceding roll and finally form the ultimate inside grooves of the sheet in a manner to utilize the stock offset by the shoulders 52 and 53 as previously brought out. The roll 23, complementing roll 31, is formed with grooves 56 (Figure 3) cooperating with the beads 64 and 65 of said roll 31 in finishing said grooves. Upon the succeeding rolls 25 to 30 inclusive are formed similar beads 67 and 68, aligned with the beads 64 and 65, which retain the shape of the grooves finally formed by the beads 64 and 65. These latter beads cooperate with grooves 69 formed in the complementary rolls 17 to 22 inclusive.

Where more than two grooves are to be formed in the sheet and such grooves are to be progressively constructed, as pointed out in my said co-pending application, additional shoulders 70, 71, 72, 73, etc., may be formed on the various upper rolls, as best shown in Figure 1, and correspondingly formed beads constructed on the lower rolls.

For the purpose of feeding the sheet between the upper and lower rolls, the portions 74 of the various rolls disposed between the respective beads and shoulders thereof are of such diameter as to engage the stock and advance it into the machine. The outer portions 75 of the rolls are smaller in diameter than the portions 74 so that the stock may be readily gathered inwardly from the sides of the strip or sheet as it is advanced and the grooves formed therein.

The drive for the various rolls is best shown in Figure 2. To the trunnions 36 of all of the rolls 25 to 32 inclusive, spur gears 77 are secured. These spur gears mesh with corresponding spur gears 78 on the trunnions 33 of the rolls 17 to 24 inclusive. These spur gears 77 and 78 have a pitch diameter equal to the distance between the axes of the cooperating rolls so that when said rolls are driven through said gears, all of the rolls travel at the same rate of speed. Interposed between the adjoining gears 78 are idler gears 79 which mesh with the gears 78 causing all of these gears to travel in the same direction. These idler gears are mounted upon stud

shafts 80 attached to the frame member 10 in any suitable manner. The train of gears, above described, may be driven through any of the gears thereof by any suitable power transmission means.

In my present invention, I associate with the previously described mechanism two rollers 81 and 82 which are mounted between the frame members 10 and 11 immediately in advance of the rollers 32 and 24. These rollers are formed with trunnions 83 and 84 similar to the trunnions 33 and 34 of the other rolls of the machine. The trunnions 83 are journaled in bearings 85 secured to the frame members 10 and 11, while the trunnions 84 are journaled in bearings 86 slidably mounted on said frame members in the same manner as the bearings 38. The bearings 85 and 86 are urged apart through compression coil springs 87 seated in sockets 88 and 89 formed in said bearings 85 and 86. For the purpose of moving the rolls 81 and 82 together, brackets 90 are employed which are secured to the upper portions of the frame members 10 and 11 through cap screws 91 in the same manner as the bars 45. These brackets are threaded to receive vertically disposed screws 100, best shown in Figures 2 and 4, which engage the bearings 86. To the upper ends of these screws are secured worm wheels 101, the same being adapted to be rotated through worms 102 mounted on a transversely disposed shaft 103. The shaft 103 is journaled in bearings 104 formed in the brackets 90 and is adapted to be rotated by means of a crank 105 secured to one end of said shaft. Through the rotation of shaft 103, the screws 100 are turned simultaneously, causing the roll 81 to be raised or lowered with respect to the roll 82 according to the direction of rotation of said shaft 103.

In advance of the rolls 81 and 82 is an idler roller 106 (Figure 2) which is provided with trunnions 107 at the ends thereof. These trunnions are journaled in bearings 108 attached to the frame members 10 and 11 by screws 109. This roller 106 directs paper from a roll or other source of supply to the rolls 81 and 82.

Upon the periphery of the roll 82, at the center thereof, is formed a relatively large gradually curved bulge 110, the length of this bulge axially of the roll 82 being substantially equal to the over all distance between the shoulders 52 and 53 of the roll 32 and serves to gather centrally of the sheet or strip sufficient stock to form the two grooves at the center of the sheet. The bulge 110 is gradually curved so that in the gathering of the stock, the sheet is not sharply distorted or bent. Operating in conjunction with the bulge 110 is a groove 111 in the roll 81, which conforms with said bulge.

These two members operating together gather the stock of the sheet, as stated.

gather the stock of the sheet, ^{start} 70
For driving the two rolls 81 and 82, the trunnions 83 and 84 adjacent the side frame member 10 are supplied with meshing spur gears 112 and 113. These gears are of equal pitch diameter and of a diameter equal to the mean diameter of the rolls so that said gears cause the rolls 81 and 82 to turn at the same rate of speed. These rolls 81 and 82 are driven from the last of the series of gears 78 through an idler gear 114 of the same nature and mounted in the same manner as the idlers 79. In this construction, all of the rolls are driven in the proper directions to cause the sheet to move along the same as the sheet passes from roller 106 and into the bite of rollers 81 and 82. 75 80

In the operation of the machine, the paper, pulled from a roll, is first drawn through a bath of water or steam and thence run over the roller 106 and through the rolls 81 and 82. As the strip or sheet of paper passes through said rolls 81 and 82, an appreciable portion of the paper stock is gathered centrally of the strip or sheet to assist in the subsequent formation of the grooves in the paper. This gathering of the stock depends upon the relative disposition of the said rolls 81 and 82. Under ordinary circumstances, the rolls will be near enough together so that in addition to gathering the paper stock they will serve as a ringer for removing the surplus water from the paper before it enters the forming rolls. By running the paper through the rolls 24 and 32 and through the succeeding rolls, the sheet is first formed with offsets and then with grooves, as previously pointed out and as more fully disclosed in my said co-pending application. When the paper finally leaves the machine, it is formed with a plurality of grooves conforming in configuration to the various beads on the former rolls. As previously stated, where the apparatus is to be used in constructing certain types of egg flats, the sheet is subsequently submitted to the operation of mechanism for forming transverse grooves therein.

My invention is highly advantageous in 115
that an exceptionally low grade of stock may
be used in the formation of egg flats with-
out appreciable danger of the paper becom-
ing torn in the gathering of the stock pre- 120
paratory to the final formation of the ulti-
mate grooves. The amount of stock gath-
ered can be accurately regulated by adjust-
ing the roll 81 with respect to the roll 82 and
said rolls operate as a wringer to remove
more or less of the surplus water from the 125
paper.

Changes in the specific form of my invention, as herein described, may be made within the scope of what is claimed without departing from the spirit of my invention. 130

Having described my invention what I claim as new and desire to protect by Letters Patent is:

1. The method of forming in a moving sheet an intermediate longitudinal groove, consisting in continually gathering a substantial amount of the stock of the sheet at the intended locality of the groove, without appreciably bending or suddenly distorting the sheet, and in thereafter forming the gathered stock to provide the groove therein. 5
2. The method of forming in a moving sheet an intermediate longitudinal groove, consisting in gathering an appreciable amount of the stock of the sheet at the intended locality of the groove, without appreciably bending the sheet, by forming a preliminary shallow groove in then bending the gathered portion of the stock to form an offset in the sheet at the locality of the groove, and in thereafter further forming said stock to provide the finished groove. 15
3. In a machine for forming sheets with longitudinal grooves therein, a number of pairs of complemental rolls, one of the rolls of the first pair having a relatively large gradually curved annular bulge, the other thereof having a groove corresponding and cooperating with said bulge to gather at the locality of the groove an appreciable amount of the stock of the sheet without appreciably bending the sheet, the following pairs of rolls embodying gathering and forming means for subsequently forming the grooves in the sheet 30 from that portion thereof gathered by the first rolls. 35
4. In a machine for forming longitudinal grooves in a sheet, a pair of complemental rolls provided with cooperating shoulders for partially forming previously gathered stock of the sheet, a second pair of rolls provided with co-operating beads and grooves for finally forming the grooves in said sheet along that portion thereof partially formed by said shoulders, and a pair of rolls in advance of said first named rolls, one of said rolls having a relatively large gradually curved bulge thereon and the other thereof having a groove corresponding with said bulge, said groove and bulge cooperating to gather the stock of the sheet preparatory to the action upon it of said other rolls in the ultimate formation of the grooves in the sheet. 45
5. In a machine for forming sheets with longitudinal grooves therein, a number of pairs of complemental rolls, one of the rolls of the first pair having a relatively large gradually curved bulge thereon, and the other roll having a groove corresponding with said bulge to gather at the ultimate locality of the grooves a substantial amount of the stock of the sheet without appreciably bending the sheet, the other pairs of rolls embodying gathering and forming means for subsequent- 60
6. In a machine for forming a sheet with a groove, a frame, a pair of complemental gathering rolls, bearings fixed relative to said frame for journaling one of said rolls, bearings movable relative to said frame for journaling the other of said rolls, means for holding said bearings in adjusted position to vary the distance between said rolls to regulate the amount of stock gathered by said rolls, and means for forming the groove in the sheet from the portion thereof gathered by said rolls. 70
7. In a machine for forming a sheet with a groove, a frame, a pair of complemental gathering rolls, bearings fixed relative to said frame for journaling one of said rolls, bearings movable relative to said frame for journaling the other of said rolls, and means for simultaneously raising and lowering said bearings to vary the distance between said rolls and regulate the amount of stock gathered thereby, and means for forming the groove in the sheet from the portion thereof gathered by said rolls. 75
8. In a machine for forming a sheet with a groove, a frame, a pair of complemental gathering rolls, bearings fixed relative to said frame for journaling one of said rolls, bearings movable relative to said frame for journaling the other of said rolls, screws cooperating with said movable bearings for moving the same relative to said fixed bearings, a shaft extending in proximity to both of said screws, gearing on said shaft and screws for simultaneously turning the screws, and means for forming the groove in the sheet from that portion thereof gathered by said rolls. 80
9. The method of forming in a moving sheet, an intermediate longitudinal groove, consisting in gathering the sheet at the intended locality of the groove by forming a preliminary shallow gradually curved groove of a width considerably greater than its depth, the amount of stock gathered being substantially that required for the final groove, and in thereafter forming the preliminary groove to provide the final groove. 85

In testimony whereof I have affixed my signature.

SWAN SMITH. 120
